SPARK PLUG STRUCTURE

Lawrence A. Hyland, Washington, D. C., assignor,
by mesne assignments, to Bendix Aviation Corporation,
South Bend, Ind., a corporation of
Delaware

Application July 1, 1929, Serial No. 375,241

66 Claims. (Cl. 123—169)

This invention relates to ignition apparatus for internal combustion engines, and more particularly to improvements in spark plug structures.

One of the objects of the present invention is to provide a novel spark plug which is so constructed as to be particularly adapted for use in aeroplane engines.

Another object of the invention is to provide a combined spark plug and cable connection which may be readily installed and disassembled for inspection and repair.

Another object is to provide a spark plug embodying novel means for maintaining the center electrode in operative position.

Another object is to provide a combined spark plug and cable connection embodying novel shielding means whereby the plug is adapted for use on engines operated in proximity to electrical apparatus, such as radio receiving sets.

A further object is to provide a structure of the above character which is not only shielded to prevent electrical interference, but is also moisture-proof.

Other objects include the provision of a shielded plug which is rugged and dependable in operation, and which is so constructed that its functions as a charge igniting device are not impaired; to provide novel means for detachably connecting the cable to the center electrode of the plug; and to provide means for angularly adjusting the ignition wire or cable relative to the spark plug body.

Several embodiments of the invention are illustrated in the accompanying drawings, wherein like reference characters refer to like parts throughout the several views, but it is to be understood that the drawings are for purposes of illustration only and are not designed as a definition of the limits of the invention, reference being had for this purpose to the appended claims. In the drawings:

Fig. 1 is an axial sectional view of a spark plug structure embodying the present invention;

Fig. 2 is a side elevation of the structure shown in Fig. 1;

Figs. 3 and 4 are sectional views taken on the lines 3—3 and 4—4 respectively, of Fig. 1;

Fig. 5 is a side elevation, partly in section, of another embodiment of the invention;

Fig. 6 is a detailed view showing a portion of the spark plug in section, and illustrating details of the clamping or latch mechanism shown in Fig. 5; and

Fig. 7 is an axial sectional view of still another embodiment of the invention.

Referring more particularly to Figs. 1 to 4, inclusive, the spark plug structure embodying the present invention comprises a body portion or shell 8, which carries a grounded electrode 9, and 5 which is exteriorly threaded at the lower end thereof to facilitate its insertion in the cylinder wall 10 of an internal combustion engine. Centrally disposed within body portion 8 is a core carrying a center electrode 11 which is surrounded by a thin tube 12 of compressible insulating material, such as mica. Adjacent its lower end, the center electrode is enlarged to provide an annular shoulder 13 against which the lower end of tube 12 abuts. The shoulder 13 also acts as 15 a support for a series of annular mica washers 14, the upper one of said washers being engaged by a cone-shaped, hollow sleeve 15 and the walls of the opening in the latter having engagement with tube 12. Surrounding sleeve 15 and in engagement therewith is a cap or gland 16 which is threaded into the upper end of body portion 8, a washer 17 being interposed between the lower end of the gland and a suitable shoulder in said body portion to form a gas-tight joint therebetween. 20 The upper end or shell 18 of gland 16 is formed as a barrel to provide a hollow cylinder or casing which is interiorly lined with a thin tube 19 of insulating material, such as mica, with the lower end of the sleeve resting on an annular shoulder 20 formed in the gland. The shoulder 20 supports a stack of annular insulating washers 21 which surrounds the tube 12 and is surrounded by the sleeve 19, the washers preferably being formed of mica. Tube 12, washers 21, and tube 19 form a continuous insulator or body which 25 extends from the upper end of cylinder 18 to a point closely adjacent the lower end of electrode 11.

Novel means are provided for retaining the center electrode 11, washers 14, sleeve 15, and washers 21 in operative relation to gland 16 and body portion 8. For this purpose the upper portion of center electrode 11 is provided with a central longitudinally extending recess 22, and 40 the upper end of said electrode is of reduced diameter to receive a washer 23 which may be formed of metal and which fits snugly within insulating tube 19. The upper tubular end of center electrode 11 is rolled or beaded over into engagement with the upper end of washer 23 and 45 whereby the center electrode and the elements associated therewith are securely clamped and held between shoulder 13, shoulder 20 and washer 23.

50 As is clearly shown in Fig. 1, the upper end

of the tubular portion of gland 16 and the upper end of insulating tube 19 extend above washer 23 to form a recess, pocket or socket for receiving the lower arm 24 of a head or cap in the form of an elbow 25 that is preferably formed of high grade insulating material, such as porcelain. The upper arm 26 of the elbow or insulating bushing 25 is provided centrally with a circular bore 27 into which extends the end of a cable 28 provided with flexible insulation 29. Secured as by means of solder or in any other suitable manner to the inner end of cable 28 is a terminal in the form of a metal cap 30, which may be provided with a recess 31 to receive the extremity of cable 28.

Novel means are provided for electrically connecting cable 28 to the center electrode 11. In the form shown, a metal rod 32 forms an outlet with, and slidably extends into the elongated recess 22 in the upper end of, center electrode 11 and the extremity of said rod is longitudinally slotted and slightly sprung so that a good electrical connection is formed with the center electrode. The lower arm 24 of insulator 25 is provided with a circular bore or recess 33 having a diameter slightly larger than the outer diameter of rod 32 in order to permit ready assembly of the parts. The upper end of bore 33 opens into bore 27 closely adjacent the inner end of the latter, and the upper end of rod 32 extends through an opening in metal cap 30. If desired, the upper end of the rod may be slotted to form a spring-like connection with cap 30 similar to the connection provided with the center electrode, but preferably said end is threaded into an opening in cap 30, as shown at 34. It will be seen that after cable 28, 29, with cap 30 attached thereto, is introduced into bore 27, rod 32 is passed upwardly through bore 33 and threaded into the opening in cap 30 whereby a strong mechanical connection is provided for cable 28. The lower arm of elbow 25 is now inserted in the upper end of the cylinder 18, whereupon the slotted end of rod 32 is forced into recess 22 and the electrical connection between the cable and center electrode is completed.

In accordance with the present invention it is desirable to provide a shielded structure, and it is therefore necessary to surround insulating member 25 with a metal coating or covering. For this purpose a sheath or rigid metal shell 35 is preferably provided for enclosing elbow 25. The metal shield or elbow may be die-cast around the insulator elbow, electrodeposited thereon, or formed in any other suitable manner, but care should be taken to prevent too close a fit between the metal elbow and the insulator elbow in order to avoid undue strains being imposed upon the latter when the plug is in use. The inner diameter of the lower arm 36 of the metal shield is greater than the outer diameter of arm 24 of the insulator elbow and also of the cylinder 18, whereby the lower arm 36 telescopically and closely engages said cylinder when the lower arm 24 of the insulator elbow is inserted in the upper end of cylinder 18. This construction provides an annular space 37 adjacent the upper end of cylinder 18 which serves to break up the capillary action of water or oil which may seep along the engaging surfaces of the cylinder and elbow, whereby a liquid-proof joint is formed. Particular attention is called to the fact that the lower arm 36 of metal elbow 35 extends downwardly beyond the lower end of arm 24 of the insulator elbow whereby said arm 24 is relieved of all strains resulting from pressures applied to the

structure. In the form shown the outer end of the upper arm of elbow 35 is provided with an interior shoulder 38 which abuts against the outer end of arm 26 of the insulator elbow 25. Said metal elbow is provided adjacent said shoulder with a laterally extending portion or hollow tension of reduced diameter for a purpose to be described hereafter.

Novel means are provided for detachably connecting elbows 25 and 35 to cylinder 18 whereby assembly and repair of the parts may be readily effected, and said means are preferably so formed that the elbows may be rotated relative to cylinder 18 in order that cable 28, 29 may be angularly adjusted relative to the spark plug body. Angular adjustment of the cable is desirable in order to avoid sharp bends, whereby the installation of the structure is facilitated and damage to insulation 29 is prevented. In the form shown, the connecting means is of the bottle cap type embodying a ring 39 which is rotatably disposed around cylinder 18 and is adapted to engage the lower surface of a collar 40, which is welded or otherwise suitably secured to the outer surface of cylinder 18 substantially in the plane of washer 23. Secured to and extending upwardly from ring 39 is a pair of arms 41 (Fig. 4) to the ends of which is pivoted a lever 42. Intermediate the curved free end of lever 42 and the points of attachment of said lever to arms 41 there are pivotally connected the lower ends of a bail 43 which extends around and is adapted for clamping engagement with the upper surface of elbow 35. Preferably the latter is provided with a lug 44 which is engaged by the bight of the bail when the latter is in clamping position.

When elbow 35 is in telescoping engagement with cylinder 18 and lever 42 is in the raised position shown in Fig. 1, bail 43 is swung into engagement with the upper surface of elbow 35 and, due to the resiliency of the parts, lever 42 may be swung downwardly to the dotted line position in Fig. 1 (the full line position of Fig. 2) to lock the parts in operative relation. By this arrangement the cable is readily attached to or detached from center electrode 11 to provide for inspection of the parts and to permit angular adjustment of the cable relative to cylinder 18. The parts may be so proportioned that cable 28, 29, elbows 25 and 35, and rod 32 may be angularly adjusted relative to cylinder 18 when the latch or securing mechanism is in locked position.

It is necessary in order to provide a shielded ignition system to shield cable 28, 29 throughout its length, and means must be provided for forming a proper and serviceable connection between the cable shield and metal elbow 35. Preferably, a flexible sheathing of woven wire 45 is employed for the cable 28, 29, and the present invention embodies novel means for detachably connecting said sheathing to elbow 35. To this end a light metal, cup-shaped member 46, which is longitudinally slotted adjacent one end thereof to provide a plurality of spring arms 47, is positioned on the flexible shield of the cable. The extremity of shield 45 is expanded around the reduced portion of elbow 35 to form a telescopic joint, as shown at 48 in Fig. 1. Cup 46 is then slid along the sheathing 45 until arms 47 are forced into clamping engagement with an annular groove suitably formed in the outer surface of the reduced portion of the metal elbow. By a proper proportioning of the annular groove a very strong connection can be provided between flexible shield 45 and metal elbow 35, and this connection co-

acts with rod 32 to retain cable 28, 29 in operative position relative to the center electrode 11. Particular attention is called to the fact that the cable insulation 29, which is usually a rubber composition, is protected from the high temperatures set up in the structure in the zone immediately adjacent to and above washer 23.

In Figs. 5 and 6 there is illustrated another embodiment of the invention wherein the elbow clamping means comprises a rotatably mounted ring 49 which carries a pair of diametrically disposed and laterally projecting pins 50 on which is pivotally mounted a lever 51. A bail 52 formed of a flat strip of metal and adapted to engage the walls of a recess 53 formed in the upper surface of the metal elbow 54 is pivotally connected to lever 51. The pivotal connections between bail 52, lever 51, and ring 49 are so disposed that the lever is swung upwardly when moved into clamping position with the free end of said lever underneath the overhanging upper arm of the elbow. This arrangement insures against accidental movement of the lever to non-locking position, but provides for ready detachment of the cable. The parts may be so proportioned as to permit angular adjustment of said cable even though the lever be in locking position.

As shown more clearly in Fig. 5, the flexible cable shield is expanded around the reduced end 59' of elbow 54, and shield and cable are mechanically bonded to said elbow by winding several turns of wire 55 around the expanded portion of shield 45. Preferably the wrapped wire is soldered to form a good connection.

Another embodiment of the invention is illustrated in Fig. 7 wherein a spark plug body 56 carries a grounded electrode 57. A center electrode 58 is mounted in an insulator 59 which is preferably formed of porcelain and is retained in operative position in body 56 by means of a removable sleeve 60. The upper end 59' of insulator 59 is of tubular form to provide a conical chamber or pocket 61 above the center electrode. Extending down into this chamber is the lower arm 62 of an insulator elbow 63 which is shielded by means of a metal elbow 64. The inner diameter of the lower arm 65 of metal elbow 64 is such as to permit telescopic engagement of said lower arm with the upper end of sleeve 60, and the parts are held in operative relation by means of a split steel ring 66 adapted to extend into annular grooves in lower arm 65 and sleeve 60, said grooves being in registry when the parts are in normal assembled position.

A cable connecting member 67 projects centrally through the lower arm of insulator elbow 63 and is retained in position in said arm by being threaded into a metal sleeve or washer 68 inserted or threaded into a suitable recess in the lower end of the arm. The upper end of conductor member 67 is sharply pointed to pierce the insulation 29 of the ignition cable 28 and make electrical contact with said cable. The shielding 45 of said cable is suitably secured in the groove 47 of reduced extension 48 of elbow 64, as by a retaining member shown in section in Fig. 7 and in elevation in Fig. 2. If desired, the parts may be so proportioned that the lower end or screw head of connecting cable member 67 is separated from the upper end of center electrode 58 whereby an extra gap is provided to insure that the plug will fire, even though the electrodes are fouled.

There is thus provided a novel spark plug structure which is particularly adapted for use

in high compression engines and engines operated in proximity to radio apparatus. The shield is combined with the plug body in such a manner that the parts may be readily installed, and disassembled for inspection and repair. Gland 16 and body portion 8, though separately formed in the embodiments of the invention illustrated, coact to form a continuous metal shield which is in telescopic engagement with the continuous shield 35, 45. A portion of the former is rigid and extends below the lower end of the insulator elbow to relieve the latter of strains, while the portion 45 is preferably flexible to facilitate the handling of the cable and its connection with the power source. It will be understood, however, that any suitable form of shield may be provided for the cable.

A strong electrical and mechanical connection is made between the cable and the center electrode of the plug, but the cable is always angularly adjustable and this without the necessity for releasing the clamping means. The center electrode of the plug is so mounted as to be retained in operative position at all times and to insure a gas-tight joint around said electrode. In actual use the plug structure constituting the subject matter of the present invention has been found efficient and dependable. Various changes may be made in the details of construction, and certain parts may be used without others. Reference will accordingly be had to the appended claims for a definition of the limits of the invention.

What is claimed is:

1. Means for connecting a spark plug cable and electrode having a recess in the upper end thereof, comprising an insulator, provided with a recess, surrounding said cable, a cap carried by the end of said cable, and a rod in electrical engagement with said cap, the lower end of the rod extending into said first named recess.

2. In apparatus of the class described, a spark plug body, a center electrode therein, a metal elbow secured to said body and having a reduced portion, insulating means in said elbow, a cable extending into the elbow, means for electrically connecting said cable and electrode, a metal shield for said cable, and a cup for detachably connecting the cable shield with the reduced portion of the metal elbow.

3. Apparatus of the class described including a spark plug body having a hollow cylindrical portion, a metal elbow having the lower arm thereof in telescopic engagement with said cylindrical portion, an insulator elbow in the metal elbow and having the lower arm thereof extending into said cylindrical portion, whereby an annular space is provided adjacent the upper end of the cylindrical portion for interrupting capillary action, current carrying means extending through said elbows, and means for operatively connecting said elbows with said cylindrical portion.

4. Means for operatively connecting complementary sections of a spark plug body including a ring rotatably mounted on said body, a collar carried by the body and having engagement with said ring, a lever carried by the ring, and a bail secured to the lever.

5. Means for operatively connecting a spark plug cable with a spark plug electrode comprising a cap secured to the end of said cable, an insulator into which said cable extends, a member having detachable engagement with said electrode

and cap, and means for rotatably connecting said insulator with the body of the plug.

6. A shielded spark plug structure for internal combustion engines comprising a body portion terminating in a hollow cylinder at the upper end thereof, a center electrode in said body portion, means forming a continuous insulator which surrounds the center electrode, said means terminating at its upper end in the plane of the upper end of the hollow cylinder and at its lower end near the lower extremity of the center electrode, insulator member extending into the open upper end of said insulating means, a cable extending into the insulator member, means extending through a portion of the insulator member for operatively connecting the cable to the center electrode, a continuous metallic shield for the insulator member and cable, a portion of said shield having telescopic engagement with said hollow cylinder and another portion of said shield being flexible to permit bending of the cable, and clamping means for detachably connecting said shield and hollow cylinder.

7. In combination, a spark plug body having a continuous metallic surface terminating at the upper end in a cylindrical portion, a metal shield surrounding said upper end, an electrode centrally disposed in said body portion, a cylindrical insulator surrounding said center electrode, an elbow formed of insulating material and having the lower arm thereof extending into the cylindrical portion of the plug, said elbow having a bore in the upper arm thereof, an insulated cable extending into said bore, means extending through the lower arm of said elbow for electrically connecting said cable and center electrode, and a metallic sheath surrounding said cable and in overlapping electrical engagement with said shield.

8. In combination with an insulated cable, a spark plug having a cylindrical portion at the upper end thereof, an insulator elbow having its lower arm extending into said cylindrical portion, the upper arm of the elbow being provided with a bore into which the cable extends, means extending through the lower arm of said insulator elbow for electrically connecting said cable and the center electrode of said plug, and rotatable means for detachably connecting said elbow and plug body whereby the cable may be removed from or angularly adjusted relative to the body of said plug.

9. Means for operatively connecting a spark plug cable with a spark plug electrode comprising an insulator member, a needle-like member extending through the insulator member for establishing electrical connection between the cable and one of the terminals of the spark plug, and a metallic sleeve threadedly engaging both said needle-like member and insulator member for retaining said needle-like member in operative position, said needle-like member having a screw head serving as the electrical connection between said cable and terminal, and also constituting the means whereby said needle-like member and cable are operatively connected prior to complete assembly of the plug.

10. A terminal connector for a spark plug having a body structure of insulating material substantially in the form of an elbow with one portion of said elbow having a rod member extending centrally therethrough with a contact formed on one end thereof in engagement with the central electrode of said spark plug, and means for securing the opposite end of the rod member

within said elbow prior to connection with said electrode.

11. An insulator for a spark plug, said insulator comprising a member having portions extending substantially at right angles one to the other, one of said portions being recessed to receive the end of an ignition wire, the other of said portions carrying an adjustable screw threaded member arranged to engage the end of said ignition wire, said screw threaded member having a contact on its extremity for establishing an electrical connection with the center electrode of the spark plug.

12. In combination with a spark plug body, a center electrode therein, insulating means interposed between the electrode and body and adapted to maintain said electrode in operative position, said body and insulating means being so formed as to provide a pocket above the upper end of the center electrode, a shielded insulator member having a portion thereof projecting into said pocket, a shielded cable extending into a recess in said insulator member, and means for establishing an electrical connection between the center electrode and cable.

13. A shielded spark plug structure for internal combustion engines comprising a body portion terminating in a hollow cylinder at the upper end thereof, a center electrode in said body portion, means forming a continuous insulator which surrounds the center electrode, an insulator member extending into the open upper end of said insulating means, a cable extending into the insulator member, a continuous metallic shield for the insulator member, a portion of said shield having engagement with said hollow cylinder, a second flexible shield surrounding the cable, and clamping means for detachably connecting said first shield and hollow cylinder.

14. A shielded spark plug and conductor comprising a casing formed of three overlapping sections, resilient means adapted to hold two of said sections in contact with each other, means for securing said shielded conductor to one of said sections, and means integral with the other two sections for securing said other two sections to each other.

15. Fastening means for a protecting cap of spark plugs comprising a member connected to the spark plug in a manner permitting relative angular displacement of said member and plug, and spring means mounted in said member and engaging the cap.

16. Fastening means for a protecting cap of spark plugs comprising a member connected to the spark plug in a manner permitting relative angular displacement of said member and plug and a spring clamp having its ends mounted in said member and an intermediate portion adapted to engage the cap.

17. In a spark plug of the type having a cylinder engaging shell carrying one electrode and a shielded conductor electrically connected to the other electrode, the combination with said conductor and shell of a shield having a cylindrical portion secured at its lower end by direct, locking contact with said shell, and having a second portion embracing the shielded conductor, and means for holding said two portions in engagement with each other.

18. The method of assembling a spark plug of the self-shielding type which comprises the steps of separately assembling the cylinder engaging outer metallic shell, the center electrode and the

parts supporting said center electrode and also separately assembling the cable receiving portion of the plug, said last named assembling process including the step of applying a metallic coating to the entire outer surface of the cable receiving portion of the plug, then inserting the cable within said cable receiving sub-assembly in a position such as to cause its metallic covering to contact said first-named metallic coating, then inserting a current conducting element in said cable receiving sub-assembly, and operatively connecting said element and cable, and finally bringing both sub-assemblies into operative connection, one with the other.

19. Fastening means for a protecting cap of a spark plug comprising a member surrounding a portion of the spark plug which is disposed beneath said cap and spring means having its ends mounted on said member and engaging the cap, said cap and spring means being angularly displaceable in relation to the plug to permit the protecting cap to face in any one of a plurality of directions as desired.

20. Fastening means for a protecting cap of a spark plug comprising a member surrounding a portion of the spark plug which is disposed beneath said cap and a clamp having its ends mounted on said member and engaging the cap, said cap and clamp being angularly displaceable in relation to the plug to permit the protecting cap to face in any one of a plurality of directions as desired.

21. Fastening means for a protecting cap of a spark plug comprising an annular member surrounding a portion of the spark plug which is disposed beneath said cap and a retaining clamp having its ends secured by said annular member and adapted for engagement intermediate its ends with said cap.

22. Fastening means for a protecting cap for a spark plug comprising an apertured member surrounding a portion of the spark plug which is disposed beneath said cap and a clamping bail bent inwardly at its ends to enable each of said ends to engage in one of said apertures, said bail having an intermediate portion engageable with the top of said cap.

23. The method of assembling a shielded spark plug which comprises the steps of making two separate sub-assemblies, one of which includes the cylinder engaging outer metallic shell, the center electrode and the parts supporting said center electrode, and the other of which includes the cable receiving portion of the plug, said last named sub-assembling process also including the step of inserting the cable within said cable receiving sub-assembly in a position such as to automatically complete the current path from said cable to said center electrode when the two sub-assemblies above described are brought together, and finally bringing said two sub-assemblies together in such a manner that one of the shielding elements of one of the sub-assemblies has engagement with a shielding element of the other sub-assembly, the extent of the registry there-between being sufficient to automatically maintain the current path between the cable and the center electrode.

24. The method of assembling a shielded spark plug which includes the step of inserting a current conductor through an opening in one part of the shielding casing, and also the step of fitting said shielding part into its proper position with respect to the cylinder engaging outer me-

tallic shell, so as to cause registry therebetween, the extent of the registry being sufficient to automatically maintain the current path between said conductor and plug.

5 25. The method of assembling a shielded spark plug which includes the step of inserting a current conductor through an opening in one part of the shielding casing and also the step of fitting said shielding part to a second part of the shielding casing, so as to cause registry therebetween, the extent of the registry being sufficient to automatically maintain the current path between said conductor and plug.

10 26. In the manufacture and assembly of spark plugs of the self-shielding type, the step of applying a metallic coating to the entire outer surface of the cable receiving portion of the plug.

20 27. In the manufacture and assembly of spark plugs of the self-shielding type, the step of applying a metallic coating to the entire outer surface of the cable receiving portion of the plug, also the step of inserting said cable through an opening in said cable receiving portion of the plug, and the further step of inserting a second current conductor through a second opening, and securing said second conductor in current conducting relation to said cable.

25 28. In combination with a spark plug including a metal shell, and a shielded conductor therefor disposed with its longitudinal axis at an angle to the longitudinal axis of the plug, an insulating cover for a portion of said conductor, a device for preventing radiation of electrical energy therefrom comprising a casing formed of complementary sections, and means adapted to hold said sections in contact with each other, with a portion of one of the sections fitting about said insulating cover.

30 29. In combination with a spark plug body, a center electrode therein, insulating means interposed between the electrode and body and adapted to maintain said electrode in operative position, said insulating means being so formed as to provide a pocket above the upper end of the center electrode, a shielded insulator member having a portion thereof projecting into said pocket, a shielded cable extending into a recess in said insulator member, and means for establishing an electrical connection between the center electrode and cable, the shields of said cable and said insulator being electrically connected with said body.

35 30. In apparatus of the class described, a spark plug body, a center electrode therein, a metal elbow secured to said body and having a reduced portion, solid insulating means in said elbow, in intimate contact in the wall thereof, a cable extending into the elbow, means for electrically connecting said cable and electrode, a metal shield for said cable, and means for detachably connecting the cable shield with the reduced portion of the metal elbow to provide an electrical connection to ground through said elbow.

40 31. In combination, a spark plug comprising a metallic cap and a stem having an outlet, a conductor connecting to said stem at the outlet, a porcelain elbow seated in said cap and enclosing said outlet and a metallic coating intimately encasing said elbow and grounded through said cap.

45 32. In combination, a spark plug comprising a metallic cap and a stem having an outlet, a conductor connecting to said stem at the outlet, a porcelain elbow seated in said cap and enclosing

said outlet and a metallic coating enclosing said conductor and a metallic coating on said elbow electrically connected with said metallic cap, said coatings being in the form of a thin sheath.

33. In combination, a spark plug comprising a metallic cap and a vertical stem having an outlet, a conductor having a connection with said stem at the outlet, a porcelain elbow mounted on said cap and enclosing said outlet and providing for the free movement of said connection therein and a thin metallic coating on said conductor and a thin metallic coating enclosing said elbow, said coatings being electrically connected with said metallic cap.

34. In a spark plug, a metallic body shell, an electrode carrying core mounted therein, a head carrying a conductor part for connection with said core electrode, said head having an external metallic shield for seating on said metallic body shell and forming a close joint therewith, and clamping means releasably holding the body shell and head in said assembled relation.

35. In a spark plug, a metallic body shell, an electrode carrying core mounted therein, a head carrying a conductor part for connection with said core electrode, said head having an external metallic shield for rotatably seating on said metallic body shell and forming a close joint therewith, and means releasably holding the body shell and head in said assembled relation, and permitting relative rotation of the head and body shell when assembled.

36. In a radio shield for spark plugs, a shielding cap adapted to be positioned over a spark plug comprising a metal shell, a body of dielectric material within the shell, said body having a lateral opening to receive a conductor and said body being formed with a circular recess in alignment with the upper end of a spark plug, and a contact means carried by the dielectric body and adapted to engage the spark plug, said contact means being adapted to project into the lateral opening to contact a conductor.

37. Apparatus of the class described comprising in combination a spark plug body having an electrode, a cable connected to said electrode, a metallic casing extending substantially the length of said electrode, a metallic cap cooperating with said casing to enclose and shield said electrode and cable, means including a bail for securing said cap to said casing, and means in contact with said casing and cap and substantially filling the space between said casing and cap and said electrode and cable for insulating said casing and cap from said electrode and cable.

38. In combination with a spark plug having a metallic casing and a radio shielded cable therefor, a shielding cap comprising a dielectric body disposed over the plug, said body being provided with a bore to receive the spark plug cable, a conductor carried by said body to make contact with the spark plug and projecting into said bore and a metallic covering on said dielectric body contacting both the casing of the plug and the shielding of the spark plug cable.

39. In a radio shield for spark plugs, a cap to cover a plug, said cap comprising a body of dielectric material having a lateral extension, said extension being provided with an axial bore extending into the dielectric body, a conductor carried by said body projecting into said bore and a metal cover around said dielectric body.

40. In a radio shield for spark plugs, a cap to cover a plug, said cap comprising a metal shell having a hollow extension on one side thereof,

a body of dielectric material within said shell having a portion of its surface in intimate contact with the shell, a portion of said dielectric body extending into said hollow extension to form a lining therefor, said dielectric body being provided with a bore to receive a conductor and contact means carried by the dielectric body.

41. In a radio shield for spark plugs, a cap to cover a plug, said cap comprising a metal shell and a body of dielectric material in the shell, a lateral extension on said shell and dielectric body provided with a bore to receive a conductor, a washer carried by the dielectric body, and a contact means disposed through said washer, the lower end of said contact means being adapted to be operatively disposed with respect to a spark plug and the upper end thereof being adapted to project into said bore to contact a conductor.

42. In a radio shield for spark plugs, a cap to cover a plug, said cap comprising a metal shell and a body of dielectric material intimately attached to said shell, said shell and body each having a lateral extension formed with a bore to receive a conductor and a contact means removably supported from said dielectric body, the upper end of said contact means being adapted to pierce the insulation of and make contact with a conductor in the bore and the lower end of said contact means adapted to extend below the dielectric body to be operatively disposed with respect to a spark plug.

43. A shield for a spark plug adapted to electrically connect the shielding of a shielded cable to the ground of the spark plug comprising, a metallic casing, an insulation material disposed within said casing and having one aperture to receive an insulated portion of said cable, and a further aperture adapted to receive a conductor part that constitutes a closure for said aperture and serving to electrically connect the plug and cable terminals, said insulation material having intimate contact with the walls of said casing.

44. A shield for a spark plug adapted to electrically connect the shielding of a shielded cable to the ground of the spark plug comprising, a metallic casing, an insulation material disposed within said casing and having an aperture to receive an insulated portion of said cable, and a further aperture adapted to receive a conductor part that constitutes a closure for said aperture and serving to electrically connect the plug and cable terminals, said insulation material having a relatively thin cross-section and being in intimate contact with the walls of said casing.

45. A shield for a spark plug adapted to electrically connect the shielding of a shielded cable to the ground of the spark plug comprising, a metallic casing, an insulation material disposed within said casing and having an aperture adapted to receive an insulated portion of said cable, and a further aperture to receive a conductor part, said conductor part serving to electrically connect the plug and cable terminals and said casing and insulation material cooperating to protect said cable.

46. A shield for a spark plug adapted to electrically connect the shielding of a shielded cable to the ground of the spark plug comprising, a metallic casing, insulation material disposed within said casing and having an aperture adapted to receive an insulated portion of said cable, and a further aperture to receive a conductor part, said conductor part serving to electrically connect the plug and cable terminals, said insulation material providing with said spark plug a dead

air chamber between said plug terminal and said cable insulation.

47. In combination, a spark plug comprising a metallic body shell and a core having a stem provided with an outlet, an insulated conductor connecting to said stem at the outlet, a dielectric member of relatively thin cross-section inclosing said outlet, a metallic coating intimately encasing said member and grounded through said shell, and a member in intimate contact with said dielectric member for segregating the insulation of said conductor from said outlet.

48. In combination, a spark plug comprising a metallic body shell and a core having a stem provided with an outlet, a conductor connecting to said stem at the outlet, a metal casing inclosing said connection and electrically spaced therefrom a sufficient distance to prevent flash over and grounded to said shell, dielectric material of thin cross-section disposed within said casing and in intimate contact with the walls thereof, and a member for segregating the insulation of said conductor from said outlet and in intimate contact with said dielectric.

49. A shield for a spark plug adapted to electrically connect the shielding of a shielded cable to the ground of the spark plug comprising, a metallic casing, an insulation material disposed within said casing and so arranged as to provide with said plug a dead air chamber, said insulation material having one aperture to receive an insulated portion of said cable, and a further aperture adapted to receive a conductor part that constitutes a closure for said aperture and serving to electrically connect the plug and cable terminals, said insulation material having intimate contact with the walls of said casing.

50. In a spark-plug having a body and a central spindle insulated from the body, the combination of a metal barrel with insulation lining extending upward from the body above the upper end of the spindle to provide a socket for the insertion of an insulated high-tension conductor into electrical connection with said spindle, a connection through which the conductor is passed and which has detachable connection with said barrel, and insulating means about the portion of the insulated conductor within said socket, said insulating means being unitarily associated with the conductor and in contact with said connection.

51. A shielded spark plug and electrical conductor cable for suppressing radio and other electrical disturbances comprising, a shielding for the plug and a shielding for the cable secured together near one end of said plug, said shielding including angularly related sections to enable said cable to extend at approximately a right angle to the axis of the plug, the shielding for the plug forming a part of the grounded portion of the plug, the insulation for the conductor of said cable extending within the plug shielding, the terminal of said conductor being electrically connected to the terminal of said plug, and means within the plug shielding for inclosing the cable insulation at the cable terminal and to electrically insulate said plug shielding from said terminal connection.

52. A shielded spark plug and electrical conductor cable for suppressing radio and other electrical disturbances comprising, a shielding for the plug and a shielding for the cable secured together near one end of said plug, said shielding including angularly related sections to enable said cable to extend at approximately a right angle to the axis of the plug, the shielding for the plug forming a part of the grounded portion of the plug, the insulation for the conductor of said cable extending within the plug shielding, the terminal of said conductor being electrically connected to the terminal of said plug, and means within the plug shielding for inclosing the cable insulation at the cable terminal and to electrically insulate said plug shielding from said terminal connection.

angle to the axis of the plug, the shielding for the plug being electrically connected to the grounded portion of the plug, the insulation for the conductor of said cable extending within the plug shielding, the terminal of said conductor being connected to the terminal of said plug, insulation material disposed within said plug shielding and around said cable, said insulation serving to electrically separate said shielding and cable-plug terminal connection and having surface contact with said shielding and means contacting with said insulation material for inclosing the cable insulation to protect the same.

53. In a spark plug, a threaded shell having a grounded electrode at its inner end, and the outer end of which shell is internally threaded; a tubular member having a threaded portion engaging said internally threaded shell part, and which member extends beyond the outer end of said shell; an electrode within said tubular member and extending part way only along the length thereof; an insulating tube within said tubular member and surrounding said electrode and extending to the outer end of said tubular member; a metallic housing detachably secured to the outer end of said tubular member; an insulating member enclosed within said housing and having a bore disposed in line with said tubular member; a supply conductor extending into said housing and insulating member and having a terminal in said bore; and a conductor within said tubular member and said bore and extending between said terminal and the outer end of said electrode, and the ends of which conductor contact the said last mentioned parts.

54. In a spark plug, a threaded shell having a grounded electrode at its inner end, and the outer end of which shell is internally threaded; a tubular member having a threaded portion engaging said internally threaded shell part, and which member extends beyond the outer end of said shell and is reduced in diameter so as to provide a thin wall portion beyond said outer end; an electrode within said tubular member and extending part way only along the length thereof; an insulating tube within said tubular member and surrounding said electrode and extending to the outer end of said tubular member; a metallic housing detachably secured to the outer end of said tubular member; an insulating member enclosed within said housing and having a bore disposed in line with said tubular member; a supply conductor extending into said housing and insulating member and having a terminal in said bore; and a conductor within said tubular member and said bore and extending between said terminal and the outer end of said electrode, and the ends of which conductor contact the said last mentioned parts.

55. A shielded spark plug for a radio receiver equipped vehicle, comprising a metallic outer shell having an opening at the top thereof, an insulating body within said shell having a recess at the top portion thereof, an electrode extending through said body and terminating in said recess, a metallic recessed apertured cap through which an insulated electrical conductor may extend attached to said shell at the opening thereof, and an insulating bushing seated in said cap in cooperative relation therewith and extending into the recess of the insulating body, said bushing snugly surrounding said conductor and the cooperation between said cap and said bushing forcing intimate contact between the end of the conductor and the terminal of said electrode when said cap is attached to said shell.

56. A shielded spark plug for a radio receiver equipped vehicle, comprising a metallic outer shell having an opening at the top thereof, an insulating body within said shell having a recess at the top portion thereof, an electrode extending through said body and terminating in said recess, a metallic recessed apertured cap through which an insulated electrical conductor may extend detachably attached to said shell at the opening thereof, and an insulating bushing seated in said cap in cooperative relation therewith and extending into the recess of the insulating body, said bushing closely surrounding said conductor and the cooperation between said cap and said bushing insuring current conducting continuity between the end of the conductor and the terminal of said electrode when said cap is attached to said shell.

57. In combination with a spark plug, a shielding elbow comprising a metallic sheath in the form of an elbow, an insulator in the form of an elbow in said sheath, a conductor having a threaded portion slidably extending through a part of said insulator from one end thereof, an insulated conductor slidably extending into the other end of said insulator at an angle to said first named conductor, and an internally threaded member secured to said insulated conductor and adapted to threadedly engage said threaded portion.

58. In apparatus of the class described, an elbow-shaped insulator having a bore therethrough, a conductor slidably extending into one end of said insulator, said conductor being threaded at the inner end thereof, a second conductor slidably extending into the other end of said insulator at an angle to said first named conductor, and internally threaded means secured to said second conductor and adapted to threadedly engage the inner end of said first named conductor.

59. In a spark plug having a center electrode and a barrel extending above said electrode to form a socket, the combination therewith of a metallic shield, means for detachably connecting said shield to said barrel, an insulator in said shield having a portion extending into said barrel, electric current conducting means extending into said insulator and having electrical connection with said center electrode, an insulated conductor slidably extending into the other end of said insulator and at an angle to said conducting means, and means for detachably connecting the adjacent ends of said conductors together.

60. In a spark plug having a center electrode and a barrel extending above said electrode to form a socket, the combination therewith of a metallic sleeve having a straight portion and an angularly directed portion, means for detachably

connecting said sleeve to said barrel, an insulating liner in said sleeve and extending into said barrel, a rigid conductor extending into the straight portion of said liner and being electrically connected to said electrode, a flexible conductor extending into said angularly directed portion of said liner, and means on said flexible conductor for threadedly engaging said rigid conductor.

61. In a spark plug having a center electrode and a barrel extending above said electrode to form a socket, the combination therewith of a metallic sheath, means for detachably connecting said sheath to said barrel, an attaching means at the other end of said sheath, a shielding conduit detachably connected to said attaching means, an insulator in said sheath having a portion extending into said barrel and having a bore therethrough, an insulated conductor extending through said conduit into said insulator, a threaded member secured to said insulated conductor, and a conductor extending into the other end of said insulator and having threaded engagement with said threaded member, said last named conductor being electrically connected to said electrode.

62. In apparatus of the class described, a rigid insulator having a bore therethrough composed of angularly related sections, a rigid conductor extending into one section of said bore, a flexible conductor extending into the other section of said bore, and means secured to said flexible conductor for threadedly engaging said rigid conductor within said insulator.

63. A spark plug shield comprising an L-shaped metallic casing having an insulating elbow integral therewith, said elbow in one arm of said casing being shaped to receive the spark plug cable and in the other arm to fit closely with the extending portion of the spark plug, in combination with means for securing said casing to said spark plug.

64. Means for shielding a spark plug and associated cable comprising a non-conducting elbow into one arm of which said cable extends, the other arm being of sufficient thickness to fit closely with said plug, and a metallic elbow surrounding said first named elbow and forming a permanently integrated single unit therewith.

65. A spark plug covering comprising an L-shaped metallic sleeve and an insulating elbow whose surface conforms to the inner contour of said sleeve.

66. A spark plug covering comprising a metallic elbow and an L-shaped insulating sleeve permanently affixed to the inner surface of said metallic elbow.

LAWRENCE A. HYLAND.
